UNITED STATES PATENT OFFICE.

WILHELM ERFURTH, OF BERLIN, GERMANY, ASSIGNOR TO DEUTA-WERKE VORMALS
DEUTSCHE TACHOMETERWERKE G. M. B. H., OF BERLIN, GERMANY.

SPEEDOMETER OF THE EDDY-CURRENT TYPE.

Application filed March 11, 1925, Serial No. 14,851, and in Germany March 29, 1924.

In speedometers of the eddy current type the specific effect of the magnet, that is to say, the rotary momentum exerted on the armature divided by the weight of the magnet is most favourable when the total or nearly the whole magnetic field traverses the armature between the magnet poles only in one direction and in a single air gap and, therefore, the magnet poles are located on both sides of the armature. Instruments of this kind are known in which the armature is either bell shaped or drum shaped and also of disc shape construction. In the first case, the bell shaped armature calls for a requisite height of the instrument, while in the case of disc shaped armatures only sets of magnets have so far been known which are composed of a number of individual magnets occupying in the axial direction a space which represents a considerable multiple of the thickness of the armature. In tachometers it is generally speaking, desirable to have as flat a construction as possible particularly in instruments which are designed to accommodate additional counting mechanism or odometers, such as for example, speed indicators for automobiles. In such cases, therefore, and in particular in eddy current tachometers, a magnet of reduced dimension particularly in vertical direction is of particular advantage. An eddy current tachometer provided with such a magnet wherein all lines of force penetrate the armature between the poles in a single air gap, the armature being of disc shape capable of easy manufacture and of being readily balanced, forms the subject of the present invention. Further advantages of the magnet reside in the fact that it can be produced in a most simple manner, for example, by stamping, and that even at high rotary speeds it is practically speaking liable to no deformation, and further that for gauging purposes its effective magnetic field may be varied within wide limits by simple means.

Fig. 1 illustrates in an elevational view the gauging mechanism and the essential parts of a speedometer of the eddy current type according to this invention.

Fig. 2 is a plan view thereof omitting, however, the pointer and counter spring.

Fig. 3 is an elevational view of a modified form of magnet.

Fig. 4 is a plan view thereof.

Fig. 5 is an elevational view of a further modified form of magnet.

Fig. 6 is a plan view thereof.

Fig. 7 is a plan view of a still further modified form of magnet.

1 is the magnet which is flat and disc shaped having one shank provided with a pole shoe 2. The effective magnetic field penetrating the disc shaped armature 4 extends between the pole shoe 2 and the end 3 of the other flat shank of the magnet. The armature 4 has its axis or shaft 5 journaled between points. The magnet 1 is rigidly connected to its driving shaft 6 by means of a magnet carrier 7 which is so shaped as to serve at the same time to equalize the mass of the magnet 1. Upon the magnet 1 being revolved by the driving of its shaft 6, the lines of force penetrating the armature 4 set up eddy currents therein by the reaction of which, as is known, a rotary momentum is exerted on the armature in opposition to the spring 8. The amplitude of the armature is proportionate to the number of revolutions of the magnet, and can in the usual manner, be read on a division according to the position of the pointer 9 thereon.

As will be understood a magnet so shaped can be readily and cheaply produced from ordinary magnet steel sheets by stamping. The centrifugal forces occurring during rotation are taken up by the greatest momentum of resistance of its cross section, which in view of the flat shape is so considerable as to practically exclude all deformation.

For gauging purposes the magnetic field between the poles 2 and 3 may be varied by means of a set screw 10 which is screwed into a lug 11 on the magnet carrier 7 projecting over the edge of the armature 4. In rotating the head of the set screw 10, the upper pole shoe 2 is caused to approach or to move away from the magnet pole 3 in which action the magnet can readily yield due to its flat construction. During setting

in this way, only a very slight partial displacement of the mass takes place in axial direction, the balance of the magnet weight in regard to its axis of rotation remaining, 5 however, the same.

The additional pole shoe may be dispensed with if as shown in Figs. 3 and 4 the magnet 12 at the place indicated at 13 is cranked up and about the disc shaped armature (not 10 shown) so that its pole 14 comes to lie above the latter opposite the pole 15.

Fig. 4 illustrates moreover how the magnet 12 is provided with an inwardly projecting lug 16 containing a bore 17 enabling 15 it to be directly secured on its driving shaft, thereby dispensing with a separate magnet carrier as shown at 7 in Figs. 1 and 2.

It is within the scope of this invention to 20 shape the magnet as shown in Figs. 5 and 6. In this case the magnet has the form of a flat closed ring 18 which is provided with a diametral web 19. The end of this web as shown at 20 forms the pole located below 25 the armature disc, while the pole above it as shown at 21 is produced by offsetting the magnet ring at the points 22. By means of a bore 23 in the web 19 this magnet 18 may likewise be readily secured on its driving shaft.

30 The ring shaped disc of the magnet may, however, be also quite flat, that is to say, have no offsetting if as shown in Fig. 7 a pole shoe 25 is secured to the magnet opposite the end of the web 24, which pole shoe 35 is offset about the edge of the armature disc.

I claim:

1. A magnetic speedometer comprising a flat disc-shaped magnet and having one pole 40 thereof in the plane of the magnet; a pole shoe mounted on said magnet and forming the other pole thereof, the free end of the pole shoe being in a plane which is parallel to the plane of the magnet; and an armature for the poles which is adapted to be rotatably mounted in a plane which is parallel to and between the planes of the pole shoe and the magnet.

2. A magnetic speedometer comprising a flat disc-shaped magnet and having one pole 50 thereof in the plane of the magnet; a pole shoe mounted on said magnet and forming the other pole thereof, the free end of the pole shoe being in a plane which is parallel to the plane of the magnet; means for rotatably mounting said magnet; and an armature for the poles which is adapted to be rotatably mounted in a plane which is parallel to and between the planes of the pole shoe and the magnet.

60 3. A magnetic speedometer comprising a flat disc-shaped magnet and having one pole thereof in the plane of the magnet; a pole shoe mounted on said magnet and forming the other pole thereof, the free end of 65 the pole shoe being in a plane which is par-

allel to the plane of the magnet; an armature for the poles which is mounted in a plane parallel to and between the planes of the pole shoe and the magnet; and means for rotatably mounting said armature.

4. A magnetic speedometer comprising a shaft adapted to be driven; a magnet carrier mounted on said shaft; a flat disc-shaped magnet mounted on said carrier and having one pole arranged in the plane thereof; a 70 pole shoe mounted on said magnet and forming the other pole thereof, the free end of the pole shoe being in a plane which is parallel to the plane of the magnet; a second shaft; a disc shaped armature mounted on said second shaft and being adapted to rotate in a plane which is parallel to and between the planes of the pole shoe and the magnet; and a spring for controlling the rotation of the second shaft.

5. A magnetic speedometer comprising a shaft adapted to be driven; a magnet carrier mounted on said shaft; a flat disc-shaped magnet mounted on said carrier and having one pole arranged in the plane thereof; a pole shoe mounted on said magnet and forming the other pole thereof, the free end of the pole shoe being in a plane which is parallel to the plane of the magnet; a second shaft; a disc shaped armature mounted 95 on said second shaft and being adapted to rotate in a plane which is parallel to and between the planes of the pole shoe and the magnet; a spring for controlling the rotation of the second shaft; and means for indicating the extent of movement of the second shaft.

6. A magnetic speedometer comprising a shaft adapted to be driven; a magnet carrier mounted on said shaft; a flat disc-shaped magnet mounted on said carrier and having one pole arranged in the plane thereof; a pole shoe mounted on said magnet and forming the other pole thereof, the free end of the pole shoe being in a plane which is parallel to the plane of the magnet; a second shaft; a disc shaped armature mounted on 105 said second shaft and being adapted to rotate in a plane which is parallel to and between the planes of the pole shoe and the magnet; means for adjusting the position of the pole shoe relative to the pole on the magnet; a spring for controlling the rotation of the second shaft; and means for indicating the extent of movement of the second shaft.

7. A magnetic speedometer comprising a shaft adapted to be driven; a magnet carrier securely mounted on said shaft; a flat disc-shaped magnet mounted on said carrier and having one pole arranged in the plane thereof, said plane being at right angles to the axis of the shaft; a pole shoe mounted on said magnet and forming the other pole thereof, the free end of the pole shoe being 120 125 130

in a plane which is parallel to the plane of the magnet; a second shaft; a disc-shaped armature mounted on said second shaft and being adapted to rotate in a plane which is parallel to and between the planes of the pole shoe and the magnet; a set screw for adjusting the position of the pole shoe relative to the pole of the magnet; a spring for controlling the rotation of the second shaft; and

a pointer mounted on the second shaft and adapted to indicate the extent of movement of the second shaft when the rotation of the magnet rotates the armature by means of the eddy currents set up therein.

In testimony whereof I affix my signature.

WILHELM ERFURTH.
